United States Patent Office

Des. 233,793
Patented Nov. 26, 1974

233,793

PIANO

Winsor D. White, Jr., Chicago, Ill., and Dennis Barket,
Cincinnati, Ohio, assignors to D. H. Baldwin Company,
Cincinnati, Ohio

Filed Sept. 1, 1972, Ser. No. 285,603

Term of patent 14 years

Int. Cl. D17—01

U.S. Cl. D56—9

FIG. 1

FIG. 2FIG. 3FIG. 1 is a front, top and right side perspective view of a piano showing our new design;

FIG. 2 is a front elevational view; and

FIG. 3 is a right side elevational view.

The side of the piano not shown is a mirror image of the side shown. The back of the piano is conventional.

We claim:

The ornamental design for a piano, substantially as shown and described.
